UNITED STATES PATENT OFFICE.

JONAS NORTHROP, OF HOPEDALE, MASSACHUSETTS, ASSIGNOR TO HOPEDALE MANUFACTURING COMPANY, OF REINFORCING, MASSACHUSETTS, A CORPORATION OF MASSACHUSETTS.

TENSION-REGULATING MECHANISM FOR WARP BEAMS.

Application filed August 16, 1921, Serial No. 422,738.

To all whom it may concern:

Be it known that I, JONAS NORTHROP, a citizen of the United States, residing at Hopedale, in the county of Worcester and State of Massachusetts, have invented certain new and useful Improvements in Tension-Regulating Mechanisms for Warp Beams; and I do hereby declare the following to be a full, clear, and exact description of the invention, such as will enable others skilled in the art to which it appertains to make and use the same.

The present invention relates to an improvement in tension regulating mechanism for warp beams.

The object of the present invention is to produce a construction by virtue of which, as the size of the beam diminishes with the consumption of the warp, the friction applied to the beam to resist its unwinding is correspondingly diminished, so as to maintain a substantially equal tension upon the warp as the warp unwinds. To the above end the present invention consists in the improved tension regulating mechanism for warp beams hereinafter described and particularly defined in the claims.

In the accompanying drawings illustrating the preferred form of the invention, Fig. 1 is a side elevation of a portion of a loom, showing the warp beam in its brackets, and the associated parts of the mechanism; Fig. 2 is a plan view of the same, the portions of the loom frame above the warp beam being removed; Figs. 3 and 4 are details hereinafter referred to.

The illustrated embodiment of the invention is described as follows. The warp beam 1 is provided with the usual gudgeons 2, supported in brackets 3, on the loom frame. One of the beam disks 4 is provided with a gear 5 which meshes with the pinion 6, mounted on the pinion shaft 7, supported in the bracket 3, and bearing on its outer end a tension drum 9. Around the tension drum 9 is a chain 10, secured at one end to the arm 11 of the bracket 12 secured to the loom frame. The chain is wound twice around the tension drum, and has a hook at its end which is hooked into a recess 13 in the flange 14 of a second or chain drum 15. The tension on the chain exerts a resistance to the turning of the tension drum 9, which, through the pinion shaft 7, is transmitted

to the warp beam. Variations in the tension on the chain vary the resistance to the unwinding of the warp beam. The chain drum 15 is rotatably mounted on the stud 16, and provided on its side with a ratchet wheel 17. The stud 16 is supported from an arm 18 of the bracket 12. Also mounted on the stud 16 alongside of the chain drum 15 is the weight arm 20, which is provided with a ratchet closure 21 and a pawl 22, which is adapted to engage the teeth of the ratchet wheel 17. Downward pressure on the weight arm 20 causes the pawl to press against a tooth of the ratchet wheel and thereby to hold the chain drum with a certain force, depending upon the position of the weight 23 on the weight arm 20. The position of this weight on the weight arm 20 is determined by the size of the warp body on the warp beam. A rock shaft 30, mounted in a bracket 31, secured to the frame of the machine, is provided on its outer end with an arm 32, which is connected by means of a link 33 with the weight 23. As the rock shaft 30 is turned upon its axis, it moves the weight outward and inward on the weight arm 20, thereby increasing and decreasing the pull exerted by the weight arm on the tension chain. On the inner end of the rock shaft 30 is secured a controller arm 34, to which is pivotally attached at 35 the warp engaging shoe 36. In order to support the shoe in such position that it will move outwardly and inwardly parallel to itself in a radial direction, a compensating link 37 is pivotally attached at 38 to the shoe 36 at one end, and at the other end is pivotally attached to the bracket 31 at 40 (see Fig. 2). As the shoe moves inward following the warp body as it is drawn off of the warp beam, the link 37, in connection with the arm 34, holds the shoe so that it moves parallel to itself and in a substantially radial direction toward the warp body. A coil spring 41 mounted on the rock shaft 30 presses the warp shoe yieldingly against 100 the surface of the warp body.

When the warp beam, is first put on the loom, and assuming it to be a full beam, the warp is drawn through the loom in the usual manner, and then the chain is wound 105 a couple of times around the tension drum 9, having its end hooked into a recess in the flange 14 of the chain drum 15. At

this time the weight arm will be in its lowered position with the weight resting on the floor 42. After the end of the chain is hooked into the recess in the flange of the chain drum, the chain drum will be turned by hand until the free slack of the chain is taken up, the chain drum affording provision for taking up more or less loose end of chain, and then the operative, holding the chain drum with one hand will raise the weight arm with his other hand, thereby swinging the warp shoe upwardly into contact with the surface of the warp body on the warp beam, the pawl 22 catching successive teeth on the ratchet wheel of the chain drum as the weight arm is lifted. When the upward motion of the weight arm is arrested by the engagement of the warp shoe with the warp body, the operative will then let go of the weight arm, and the weight 23 pressing upon the weight arm 20 will tend to turn the chain drum in a direction to cause a pull to be exerted upon the tension chain to apply friction to the tension drum. As the warp is consumed, the warp shoe will follow in, pressing against the warp body, the spring ~~11~~ pressing it inward as far as it may, and thereby the position of the weight on the weight arm is determined by the radius of the warp body, causing the weight to exert a greater tension upon the tension chain when the warp body is large, and gradually reducing the amount of such tension by pulling in the weight toward the stud 16 as the warp body decreases in size.

Having thus described the invention, what is claimed is:

1. Tension regulating mechanism for warp beams having, in combination, a

tension drum adapted to be connected with the warp beam, a tension member having one end secured to a stationary part of the loom wound around the tension drum, a chain drum to which the free end of the chain is attached, a weight arm, a weight, a pawl and ratchet connection between the chain drum and weight arm, and means for moving the weight on the weight arm to cause it to exert a less tension upon the tension member as the size of the warp beam decreases.

2. Tension regulating mechanism for warp beams having, in combination, a tension drum adapted to be connected to a warp beam, a friction member with one end fastened, its body wound around said tension drum, and the other end secured to a second drum, a weight arm upon which the second drum is mounted, a weight on the weight arm and a ratchet connection between the weight arm and second drum.

3. Tension regulating mechanism for warp beams having, in combination, a tension drum, a tension member having one end secured to a fixed part of the loom, its body wound around the tension drum, and the other end connected to a second drum, a weight arm on which it is mounted, a weight on the arm, a warp shoe for engaging the surface of the warp on the warp beam, means for pressing the warp shoe against the surface of the warp, and connection between the warp shoe and weight for moving the weight in a direction to cause a diminution of the tension on the friction member with the diminution in size of the warp on the warp beam.

JONAS NORTHRUP.
